To all whom it may concern:

Be it known that I, CARL MÜLLER, a citizen of the United States, residing at Chicago, in the county of Cook and State of Illinois, have invented and produced a new and original Design for a Font of Printing-Type, which I call "Spinner Script," of which the following is a specification, reference being had therein to the accompanying printed speci-

The new design consists of a font of printing-type, in which the letters and figures are inclined backward, and are heavily shaded, mostly on the lower part of the bodies of the
15 letters and figures, some of the letters having

the heavy shading on their commencing and their terminal lines, all as fully and exactly shown in the accompanying printed specimens.

What I claim as new, and desire to secure by Letters Patent, is—
